CRYSTAL HOLDER

Joseph G. Beard, Springfield, Mass., assignor to
Westinghouse Electric & Manufacturing Com-
pany, East Pittsburgh, Pa., a corporation of
Pennsylvania

Application October 18, 1934, Serial No. 748,853

6 Claims. (Cl. 171—327)

My invention relates to crystal holders and more particularly to improvements in such holders for the protection of the crystals housed therein, to prevent wear and possible breakage 5 thereof during handling.

In connection with the stabilization of the frequency of radio apparatus, it has been standard practice to utilize some mechanical vibrating element for the purpose, having a natural 10 frequency of vibration of the order of that desired in the radio circuit. One of the best known elements of this character is the quartz crystal. Such crystals are prepared from natural quartz 15 crystals and are reasonably small in size, the size or more particularly the thickness thereof decreasing as the desired frequency increases in value so that at the higher radio frequencies, crystals become very thin and fragile.

The crystals, when once cut and calibrated, 20 are mounted in their holders and the holders are then usually sealed to prevent unauthorized tampering with the crystal.

In mounting crystals in the holders, the crystals are loosely placed within a spacing element 25 located within the holder and electrodes are positioned one below and one above the crystal, the crystal usually resting upon the lower electrode. The upper electrode sometimes rests upon the upper surface of the crystal and in direct contact 30 therewith, and in other instances, the upper electrode is maintained in spaced relationship to the crystal.

In either case, however, it has been found that the looseness of the crystal in the holder permits 35 it to move about in the holder and become subject to shocks and jars, to which the holder may be exposed. This occurs during shipment of the crystal holder and its contents, and also when the holder is embodied in apparatus such as portable frequency standards for checking the frequency of broadcast stations, these standards being mounted on trucks whereby they may conveniently be moved to any desired location. These jars and shocks are very apt to crack the 40 crystal and render it useless or cause wearing of the crystal resulting in a change from its calibrated frequency, requiring in either case that a new crystal be prepared and substituted therefor.

Consequently, it is an object of my invention to 45 eliminate such hazards in the handling of crystal holders and their contents.

A further object of my invention is to provide 50 a holder with means for protecting the crystal against shocks or jars when such crystal is not in use.

A further object of my invention is to provide 55 a crystal holder with means which will protect a crystal against injury during handling and which will automatically permit the crystal to function

upon connecting the holder into the apparatus with which it is to be used.

Additional objects of my invention will be disclosed in detail in the following description thereof, taken in connection with the accompanying drawing, wherein I have disclosed two embodiments of my invention.

Figs. 1, 2 and 3 relate to one embodiment wherein the upper electrode rests on the upper surface of the crystal and in direct contact there- 10 with; and,

Fig. 4 illustrates the second embodiment of my invention wherein the upper electrode is maintained in spaced relationship to the crystal.

Referring to Figs. 1, 2 and 3, the crystal holder 15 disclosed is comprised of two parts, a base or crystal supporting portion 1 and the cover 3 for enclosing the crystal 5. The base portion is preferably of metal and when of such material, it comprises the lower electrode. The crystal is 20 supported on this electrode and maintained against substantial lateral movement or shifting by means of a plurality of upstanding pins 7 of insulating material, so arranged as to permit of the crystal being disposed between them to prevent 25 lateral shifting thereof. The upper electrode 9 rests on the upper surface of the crystal and in direct contact therewith.

A suitable bar 11 preferably of metal, extends 30 across the upper surface of the upper electrode and is made integral therewith or is otherwise suitably attached thereto, the bar being of such a length as to extend a substantial distance on either side of the electrode.

The cover of the holder rests on the base por- 35 tion and is suitably attached thereto by any well known mechanical means, such as bolts or machine screws and encloses the crystal, the upper electrode and the bar extending thereacross. The center of the cover is perforated and threaded to receive a terminal 13 which is electrically 40 connected to the upper electrode and cross bar by means of a very weak and flexible spring 15 joining the terminal and the cross bar at its center, the spring exerting no appreciable pressure 45 against the upper electrode, but functioning merely as a flexible connecting link.

On the upper surface of the cover, there is mounted a leaf spring 17 preferably of a shape to conform to the shape of the holder, and this 50 is attached to the cover at one spot 19 leaving the spring substantially free except at its point of attachment. At diametrically opposite points on the cover directly above the ends of the bar element, openings are provided through which 55 extend pins 21, these pins being preferably of insulating material, and attached to the leaf spring. The pins are of such length as to transmit pressure from the spring against the ends of the bar element. Pressure on the ends of the 60

bar element will naturally bring pressure to bear against the crystal and between the crystal and its electrodes, thus preventing movement of the crystal should the holder be subject to jars or shocks. Consequently, the crystal under pressure will be protected against these hazards.

That portion of the circular spring diametrically opposite to the point of attachment to the cover may be bent upwardly to form a lip 23 to conveniently receive and permit of the insertion of a finger 25 or other suitable element. This element may constitute a part of the apparatus, in connection with which the crystal is to be used, and may be so disposed as to automatically raise the spring 17 upon positioning the holder in said apparatus. Thus as the finger finds its way under the spring it lifts it from its normal position, thereby removing the pressure on the cross bar and consequently removing the pressure from the crystal. The crystal thereby becomes free to vibrate and is adapted to function in the control of the frequency of the apparatus.

The radio apparatus may be so constructed that upon inserting the holder in its proper position in the apparatus, the bottom electrode and the upper terminal will both make suitable contacts with the apparatus, whereby the crystal will be operatively included in the circuit. At the same time, the spring may be lifted by the finger or other suitable element on the apparatus, placing the crystal in condition for operation.

In the construction of Fig. 4, the holder comprises a base 29 preferably of metal constituting the bottom electrode, this electrode being provided with a shoulder, on which is mounted a cylindrical tube 31 of insulating material, such as quartz, to constitute the cylindrical walls of the holder. The upper electrode 33 is provided with a similar circumferential shoulder as that of the bottom electrode, and is mounted on the upper edge of the cylindrical walls. The crystal 35 is positioned to rest on the bottom electrode and in direct contact therewith, being suitably spaced from the walls of the housing by a crystal spacing element 37. The walls of the holder are of such a height as to provide the necessary spacing between the crystal and the upper electrode.

In the center of the bottom electrode there is an opening extending clear through to the electrode, in which opening a pin 39 of insulating material is disposed, which is attached at its external end to a leaf spring 41, one end of which is secured to the bottom electrode, the other end of which is deformed to form a lip 43 to permit of easy and convenient insertion of an element 45 adapted to separate the spring from the bottom electrode. In its separated position, the crystal is permitted to rest in contact with the bottom electrode and is adapted to function as a frequency controlling device. Upon withdrawal of the separating element, however, the spring member will drive the pin upwardly against the crystal and is of sufficient length to clamp the crystal to the upper electrode against movement with respect thereto.

The element for separating the spring from the bottom electrode to permit of the oscillation of the crystal may comprise part of the radio apparatus in which the crystal is to be used, and will automatically render the crystal operative

upon the connection of the holder into the apparatus. As in connection with the embodiment of Figs. 1, 2 and 3, contact with the electrodes and separation of the spring from the bottom electrode to permit of the operation of the crystal may take place simultaneously when connecting the holder into the apparatus with which it is to be used.

Since the spring separating element of the embodiment of Fig. 4 becomes clamped against the bottom electrode and in surface contact therewith, it may constitute at the same time one of the connections which connects the crystal into the circuit.

While I have disclosed my invention in great detail, it is subject to minor changes without departing from the scope of my invention, and I, therefore, do not desire to be limited to the details, as shown, except as may be determined by the prior art and the appended claims.

I claim as my invention:

1. A crystal holder comprising in combination a support for a crystal comprising an electrode, a second electrode in spaced relationship to said first electrode, a crystal between said electrodes, spring means external of said holder for normally maintaining said crystal in pressure engagement with one of said electrodes, said means being releasable whereby to remove the pressure from said crystal to permit of vibrational movement thereof. 30

2. A crystal holder comprising in combination a support for a crystal comprising an electrode and a crystal on said electrode, a cover for said holder, a spring affixed to said cover externally thereof, and means extending through said cover to transmit the pressure of said spring to said electrode and crystal. 35

3. A crystal holder comprising in combination a support for a crystal comprising an electrode and a crystal on said electrode, a cover for said holder, a spring affixed to said cover externally thereof, and means extending through said cover to transmit the pressure of said spring to said electrode and crystal, and means for releasing said crystal and electrode from the pressure exerted by said spring. 45

4. In combination, radio apparatus whose frequency is to be controlled, a crystal control unit for controlling the frequency of said apparatus, said control unit comprising a holder for a crystal, means on said holder for normally maintaining said crystal under pressure against vibration or accidental movement, and means on said apparatus for removing said pressure means from engagement with said crystal during operation of said crystal in said apparatus. 55

5. A crystal housing comprising means for supporting a crystal, resilient means external of said housing for bringing pressure to bear against a crystal in said housing and means for releasing such crystal from the pressure influence of said resilient means. 60

6. A crystal housing comprising an enclosed chamber, means for supporting a crystal therein, resilient means mounted externally of said housing and adapted to bring pressure to bear against said crystal to prevent movement thereof in said housing, said pressure means being releasable whereby to remove the pressure from the crystal. 65
